CLAIM

The ornamental design for a display screen or portion thereof with graphical user interface, as shown and described.

DESCRIPTION

FIG. 1 is a front view of a display screen or portion thereof with graphical user interface, showing my new design in a first embodiment;

FIG. 2 is a front view of a display screen or portions thereof with graphical user interface, showing my new design in a second embodiment; and,

FIG. 3 is a front view of a display screen or portions thereof with graphical user interface, showing my new design in a third embodiment.

(Continued)

The dashed broken lines illustrating portions of the graphical user interface form no part of the claimed design.
 The dot-dash broken lines illustrating the display screen or portion thereof form no part of the claimed design.

1 Claim, 3 Drawing Sheets
